UNITED STATES PATENT OFFICE.

WILLIAM J. GROTHUIS, OF ELKHART, INDIANA, ASSIGNOR TO SANITARY STEEL COUCH COMPANY, OF ELKHART, INDIANA, A CORPORATION OF INDIANA.

KNOCKDOWN FOLDING COUCH.

No. 893,842.

Specification of Letters Patent.

Patented July 21, 1908.

Application filed November 30, 1906. Serial No. 345,650.

To all whom it may concern:

Be it known that I, WILLIAM J. GROTHUIS, a citizen of the United States of America, and resident of Elkhart, Elkhart county, Indiana, have invented a certain new and useful Improvement in Knockdown Folding Couches, of which the following is a specification.

My invention relates to folding couches, and more particularly to those having light steel or metal frames. Couches of this character have been made which were satisfactory in use, but prior to my invention they could not be shipped economically. While they were light, they could not, owing to the shape and disposition of the legs, be packed closely together, and high freight rates were invariably the case. For the same reason, the users could not conveniently store a couch of the old type. With my invention, however, the couch is of a knock-down character, the legs folding under to permit the couch to be shipped in a flat condition. In this way, the couch is, in addition, more conveniently and economically stored. Also, in accordance with my invention, the knock-down arrangement of the couch is of such character that no special skill or tools are required in setting it up. Consequently, I accomplish a saving to the manufacturer without inconvenience to the user.

In the accompanying drawings, Figure 1 is an end elevation of a couch embodying the principles of my invention, showing the same open. Fig. 2 is a longitudinal section on line 2—2 in Fig. 1. Figs. 3 and 4 are enlarged detail views of the construction. Fig. 5 is a view similar to Fig. 1, but showing the couch closed or folded. Fig. 6 is a partial side view of the couch in a knock-down condition. Fig. 7 is an underneath plan view of one end of the couch in a knock-down condition. Figs. 8 and 9 are detail views of different parts of the construction.

The couch may be of any suitable type, but is preferably built of steel or other metal parts, and is composed of a body A and two folding sides or wings B. These wings or sides are hinged to the body at b, and are adapted to drop down, as shown in Fig. 5. The body is provided with legs C, which raise the couch a suitable distance above the floor. Said legs are arranged in pairs at opposite ends of the couch, and the members of each pair are rigidly connected by cross-bars c.

Brace bars c¹ swingingly connect the legs with the side rails a of the bed or body. Ordinary bolts D, two for each end of the couch, secure the upper ends of the legs to the end beams a¹ of the body. It will be seen that the legs are of angle iron, and that their upper ends engage outside the rails a and inside the beams a¹, which rails and beams are also preferably of angle iron. Furthermore, it will be seen that the upper ends of the legs, when unfolded, are interposed between the depending flanges a²—a² of the end bars a¹—a¹ and the ends of the rails a—a, slight space being left for this purpose, to make a more rigid and compact and serviceable structure. In this way, the upper ends of the legs engage just outside of the side bars a, and in locking engagement therewith. With this arrangement the upper ends of the legs are locked against displacement, even before the screws or bolts D are inserted. Consequently very little strain if any is imposed upon the said bolts or screws.

The top or supporting structure of the bed or body is composed of slats E having their ends secured to the beams a¹ by coil springs e. Said swinging sides or wings B are also preferably composed of angle iron frames strung with slats b¹ and coil springs b². The rails a are elevated at each end, so that the entire upper surface or flat supporting structure is held above the body frame of the couch. As shown, the legs are provided with slots c² adapted to receive the deflectable braces F which are pivoted on the sides B, preferably by rivets or bolts f. These braces F have notches f¹ adapted to engage the lower edges of the slots c², as shown in Fig. 1. When the braces are lifted, then the sides B can fold into the position shown in Fig. 5, the braces projecting loosely through the said slots. When the bolts D are removed, the legs C can be folded under the couch, as shown in Figs. 6 and 7, thus adapting the couch to be shipped in a flat or knock-down condition. The user can easily insert the two bolts when the couch is to be used, and thus a great saving in cost of transportation is gained at no inconvenience to the user. In fact, the user is benefited as well, because the couch can, with my invention, be knocked down and stored in a flat condition. When the legs are folded underneath the braces F are disengaged from the slots in the legs. The legs are secured inside of the end bars a¹

of the top of the couch, and said end bars rest upon the upper ends of the legs, which latter when folded are entirely inside of the end bars, and wholly within the area of the extensible top of the couch. In this way the legs do not project beyond the ends of the couch when knocked down for shipment.

What I claim as my invention is:

1. In a couch, end bars for the same, side rails connecting said end-bars, angle-iron legs, a single link pivotally connecting each leg with one of the side rails, and means for removably securing the upper ends of said legs to the end bars, the upper ends of said legs extending outside of the said rails, and also between the ends of the rails and the inner sides of the end bars.

2. In a couch, end-bars for the same, side rails connecting the end-bars, angle-iron legs, a single link pivotally connecting each leg with one of said rails, and means for removably securing the tops of said legs inside of said end bars, each link having one end pivoted inside of an angle-iron leg and the opposite end pivoted on the outside of a side rail.

3. A folding or knock-down couch having swinging side members, folding legs provided with slots, said legs when folded lying entirely inside of the ends and sides of the couch, means for rigidly connecting together the two legs at one end of the couch, means for rigidly connecting together the two legs at the other end of the couch, side bars having upturned ends engaging said legs, and braces pivoted on said members and provided with notches adapted to engage the lower edges of said slots, when the legs are unfolded, to support the said members in horizontal position, said legs adapted to be unfolded to bring said slots into position to receive said braces, said braces adapted to fold upon the bottoms of the sides when the legs are folded.

4. In a folding or knock-down couch, the combination of folding side members, folding legs connected in pairs, one pair at each end of the couch, means for hinging the legs to swing flat-wise upon the bottom of the couch, and entirely inside of the ends of the couch, means for securing the legs in upright positions to support the side members in either vertical or horizontal positions, side bars having ends for holding the tops of the legs in place, and braces pivoted on the side members and adapted to removably engage said legs when the latter are unfolded, and adapted to fold upon the bottoms of the sides when the legs are folded.

5. A folding or knock-down couch having swinging side members, folding legs connected in pairs, one pair at each end of the couch, means for hinging the legs to swing flat-wise upon the bottom of the couch, and entirely inside of the ends of the couch,

means for securing the legs in upright positions to support the side members in either vertical or horizontal positions, side bars having their ends disposed immediately inside of the axes of said side members, and means whereby the legs when unfolded support the side members in position to extend the area of the couch, adapted to fold upon the bottoms of the sides when the legs are folded and the sides unfolded to make the couch flat.

6. In a folding or knock-down couch, the combination of a flat bed or body, swinging sides hinged thereto, folding legs connected in pairs, swinging braces connecting the legs with the body, each leg having only a single brace pivoted thereon, removable means for disconnecting the upper ends of the legs from the body, side bars secured to the ends of the bed or body at points immediately inside of the hinges of the sides, and braces pivoted on the sides and adapted to engage the legs, the ends of the couch resting upon and overhanging the upper ends of the folding legs, so that said legs have their upper ends covered when unfolded and secured in place, said legs and all said braces being adapted to fold flat-wise upon the bottom of the body and sides, said legs adapted to be unfolded to support the sides in position to extend the area of the couch.

7. A folding or knock-down couch having a top provided with means for unfolding or extending it laterally to present a flat top of sufficient width, side bars disposed immediately inside of said means, and having knock-down or foldable legs connected to swing toward each other from opposite ends of the couch and adapting the same for shipment in a flat condition with the legs folded and the top unfolded, each leg adapted to be swung into position to keep the top extended, as set forth.

8. In a folding or knock-down couch, the combination of end bars, side bars connecting the end bars, a supporting fabric or structure stretched from one end bar to the other, folding legs connected in pairs and having their upper ends disposed underneath and inside of said end bars, but outside of said side bars, so that the end bars rest upon and cover the upper ends of the legs, means for detaching the upper portions of said legs from the said end bars, to permit the two pairs of legs to fold toward each other upon the bottom and outsides of the side bars, with the upper ends of the legs within the area between the end bars, but in line with the side bars, and braces each having one end pivoted to a leg and the other end pivoted to a side bar, each leg having but one brace pivoted thereon.

9. In a knock-down couch, a top having folding sides, folding legs, and means by which the legs when unfolded keep the top unfolded, adapted to lie flatwise on the bot-

toms of the sides when the legs are folded and the sides unfolded to make the couch flat, said legs being connected in pairs at opposite ends of the couch, the pair of legs at one end 5 of the couch being adapted to fold underneath the same and toward the pair of legs at the other end thereof, said legs when folded lying entirely inside of the ends of the folding top and between the folding sides, and side 10 bars lying inside the tops of the legs when the latter are in use.

10. In a folding or knock-down couch, the combination of end bars, side bars connecting the end bars, a supporting fabric or structure 15 stretched from one end bar to the other, folding legs connected in pairs, means for detaching the upper portions of said legs from the said end bars, to permit the two pairs of legs to fold toward each other upon the bottom 20 tom of the side bars, braces each having one end pivoted to a leg and the other end pivoted to a side bar, each leg having but a single brace pivoted thereon, folding sides for the top of the couch, hinged to the end bars at 25 points outside of the ends of said side bars, and means for supporting the sides on the legs when the latter are unfolded, adapted to lie flatwise on the bottom of the sides when the legs are unfolded and the sides unfolded 30 to make the couch flat, said legs being of a height to lie wholly within the area between the end bars when the legs are folded.

11. In a couch, the combination of end bars of angle iron, side bars dropped slightly 35 but turned up at their ends to engage inside of said end bars, folding side members hinged to the ends of said end bars, at points immediately outside of the ends of said side bars, a fabric stretched between said end bars and 40 folding side members, a pair of folding legs for each end bar, a single link swingingly connecting each leg with one of said side bars, means for detachably securing the tops of 45 said legs within and underneath said end bars, and means for supporting said folding side members on the legs when the latter are unfolded.

12. In a couch, the combination of folding side members, folding legs, means for supporting the side members horizontally by the 50

unfolding or upright positioning of the legs, side bars having their ends engaging the tops of the legs, and means by which the folding movements of the side members are in a vertical plane at right angles to the vertical 55 plane of the folding movements of the legs, said couch adapted to be made flat by folding the legs and unfolding the side members.

13. In a couch having a top and folding sides therefor, swinging braces for said folding sides, folding legs adapted to swing into position to receive said braces, and means for fastening the tops of the legs inside of the top, as set forth.

14. In a knock-down couch, a rigid frame 65 composed of end and side bars, a pair of legs for one end of the couch, a pair of legs for the other end of the same, and means for detachably securing the upper ends of said legs in place between the end bars and the ends of 70 the side bars.

15. In a knock-down couch, a rigid frame composed of end bars and side bars, two rigidly connected legs for one end of the couch, a similar pair of legs for the other end of the 75 same, and means for detachably securing the upper ends of said legs to the end bars and in locking engagement with the ends of the side bars.

16. In a knock-down couch, a rigid frame 80 composed of end and side bars, the end bars projecting beyond the side bars, swinging sides hung on the ends of said end bars, legs for each end of the couch, means for detachably securing said legs to the inner sides of 85 the end bars at points outside of the ends of said side bars, and means for detachably supporting said swinging sides on said legs.

17. In a knock-down couch, a rigid frame composed of end and side bars, legs for said 90 couch, and a single screw or bolt for securing the upper end of each leg inside of an end bar and in locking engagement with the end of a side bar.

Signed by me at Elkhart, Indiana, this 24th 95 day of October, 1906.

WILLIAM J. GROTENIUS.
